WATERMILL LAWN AND GARDEN ORNAMENT

Edward Fier, Jr., Mundelein, Ill., assignor, by mesne assignments, to Lawn Ware Products, Inc., a corporation of Illinois

Filed June 16, 1969, Ser. No. 17,707

Term of patent 14 years

Int. Cl. D31

U.S. Cl. D35—1

FIG. 1 is a side perspective view of a watermill lawn and garden ornament (of which the other side is identical) showing my new design;

FIG. 2 is a front elevation of FIG. 1; and

FIG. 3 is a rear elevation of FIG. 1.

I claim:

The ornamental design for a watermill lawn and garden ornament, substantially as shown and described.
